ELECTRICAL DEVICE

Filed March 3, 1928

UNITED STATES PATENT OFFICE

LOUIS A. M. PHELAN AND PAUL S. BEAR, OF ELKHART, INDIANA, ASSIGNORS, BY MESNE ASSIGNMENTS, TO MINNEAPOLIS-HONEYWELL REGULATOR COMPANY, OF MINNEAPOLIS, MINNESOTA, A CORPORATION OF DELAWARE

ELECTRICAL DEVICE

Application filed March 3, 1928. Serial No. 258,859.

The present invention relates to an improved form of electrical device applicable to the frequent closing and opening of electrical circuits with a minimum of deterioration in the device.

Our invention comprises an hermetically sealed vessel containing a quantity of metallic conducting fluid, electrodes extending through a pinch-seal at one end of the container and adapted to make electrical contact with the conducting fluid, and an annular dam of refractory material disposed within the container in such a manner that it will serve to divide the metallic conducting fluid into two portions, each of which portions is in contact with one electrode when the device is in a substantially horizontal position. On slightly tilting the device, however, one portion of the metallic conducting fluid will flow over the dividing dam, and merge with the other portion, thus providing a continuous metallic conducting path for the electrical current from one electrode to the other.

In order to facilitate the rising of the conducting fluid over the dam, the inner face of the same is inclined with respect to the central axis of the tube. The sides of the dam are made preferably straight and vertical so that when the device is tipped in the opposite direction, the metallic fluid will separate practically instantaneously into two portions. By reason of the construction of the dam, this action will occur on the inclined face thereof, and hence any arcing that may take place on the parting of the fluid, when an electrical current is traversing the same, will occur on the dam and away from the walls of the container.

The dam is substantially annular in shape, but may be split or have a section removed from its upper portion. Both of the electrodes may enter the vessel from the same end, one of the electrodes passing the split portion of the annular dam when the same is so constructed as to permit of this contingency. This makes it possible to employ a pinch seal construction thus lowering the cost of production and simplifying the construction of our improved electrical contact de-

vice. The dam is held in place by a refractory cement.

One of the objects of our invention is to provide an electrical contact device in which a refractory dam serves to separate a metallic conducting fluid, such as mercury, into two portions, and so to construct the dam that two electrodes, each of which contacts with a portion of the metallic fluid, may enter the container housing the fluid, dam and electrodes, from the same end. 55

Another object of our invention is to provide an electrical contact device which comprises a glass container into which two electrodes extend through a pinch seal, one of these electrodes being in contact with one portion of a body of mercury and the other electrode extending through the split in the refractory dam and ending within the annular dam so as to make contact with the second 60 portion of the mercury. 70

Another object of our invention is to provide an improved electrical contactor construction in which the arcing caused by the separation of the mercury occurs away from the walls of the contactor so that the same may not be cracked or otherwise injured by the heat of the arc, while at the same time the conducting wires leading to the electrodes may both enter the container of the contactor at the same end. 75

Another object of our invention is to provide an electrode of such characteristics that it will not cause the glass of the container to crack at the seal, and also will have the property of being slightly wetted by mercury. 85

Other objects will appear in connection with the description hereinbelow, and the drawings that form a part of the present specification. 90

In these drawings:

Figure 1 is a side elevational view of one modification of an electrical contactor made in accordance with our present invention;

Fig. 2 is a top view of the same;

Fig. 3 is a cross-sectional view showing the appearance of the same, taken along the line 3-3 of Fig. 1 and looking in the direction of the arrows; 95

Fig. 4 is a perspective view of the slotted refractory dam;

Fig. 5 is a side elevational view of another modification of an electrical contactor embodying our present invention;

Fig. 6 is a view similar to that of Fig. 1, showing the device in the position when current is passing through the conducting fluid;

Fig. 7 is a side elevational view of a still further modification of an electrical contactor embodying the present invention; and

Figs. 8, 9 and 10 show the positions assumed by meniscuses of liquids in contact with various materials.

Referring to the drawings, it will be seen that our improved contact device comprises a container 11, which may be of glass, or such special glass as pyrex, or of fused silica such as vitreosil and the like. This container is preferably in the form of a short tube. One end of the tube 11 is closed by a pinch-seal 12 through which, tightly sealed into the glass, two conducting wires 17 and 18 extend. These wires may be of platinum, but we prefer to employ a special form of wire known as Dumet wire, which is copper clad and produces an air-tight seal when imbedded in glass.

Welded to the Dumet wires 17 and 18, respectively, there are two metallic contacting electrodes 19 and 20. These may consist of iron, tungsten, nickel, nickel-iron alloys, chromium-iron alloys, or other similar materials not adversely affected by nor affecting mercury. For reasons that will be more fully set forth hereinbelow, we prefer to employ substantially pure nickel. The weld 30 between the Dumet and the nickel wire lies preferably just within the inner end of the pinch-seal 12, as the Dumet wire must not be allowed to come into contact with the mercury 13 and 14 as it would contaminate the same. The mercury, as shown in the figures, forms two portions, 13 and 14, which are separated by a refractory dam 15, the portion 13 preferably being of a larger mass than the portion 14.

This dam 15 is preferably made of unpolished porcelain in order that a slightly roughened surface is obtained thereover and may be in the general form of a split or slotted ring, as illustrated in Fig. 4. Although ordinarily made of porcelain, the dam may be made of any heat-resistant or refractory material such as ignited soapstone, sometimes termed "lava" or of a similar hard inert and refractory material, provided only that the same is of a nature that will not react with the mercury, nor cause the contamination of the latter or the deterioration of the electrodes. Preferably, also, the material constituting the dam should be non-wettable by mercury, and should be slightly roughened so that the mercury will pass rapidly thereover without in any way adher-

ing to it. The inner surfaces of this ring are tapered, so that the ring will be thinner at one end than at the other. This annular dam 15 is so disposed within the tubular glass container 11 that it lies athwart the mercury, thereby dividing it into two portions 13 and 14 when the circuit through the contactor is interrupted.

The outside diameter of the annular dam 15 is slightly less than the inside diameter of the glass container. The dam is attached to the glass walls, and held rigidly in position, by a refractory and electrically insulating cement, which may consist of a pasty mixture of asbestos, aluminum oxide and sodium silicate. This cement forms a mercury-tight joint 22 between the glass walls of the container and the outer periphery of the refractory dam 15 and thus eliminates all possibility of a short circuit being established underneath the dam. It is desirable that such cement have a coefficient of expansion approximately the same as that of the material composing the container, as otherwise the alternate heating and cooling of the dam may cause the container or the dam to crack by reason of the strain produced by unequal expansion of the container and the dam. A suitable formula or compound for a cement, when the container is made of glass and the same is made of a good grade of porcelain, is:

Parts
Aluminum oxide, Al_2O_3 ----- 30
Asbestos powder, $Mg_3Si_2O_7 \cdot 7H_2O$ ----- 70
Sodium silicate, $Na_2Si_4O_8$, sufficient to make a syrup-like paste. 100

The nearer the coefficient of expansion of the glass is to that of the porcelain dam, the less asbestos is to be used in the above formula. Magnesium silicate, $MgSiO_3$, magnesium oxide, MgO , may replace the asbestos. The sodium silicate may also be diluted with some water before use. Another cement that has proven satisfactory is made up of lead phosphate, $Ph_3(PO_4)_2$ and sodium silicate. This is especially desirable when the glass employed has a high coefficient of expansion.

In positioning the dam 15, the split portion or slot is placed uppermost, and the dam is spaced nearer the end through which the electrodes enter the container. The cement is applied to the outer surface of the annular dam in sufficient amounts to completely fill the space remaining between the dam and the interior surface of the glass, whereupon it is allowed to harden.

The upper electrode is of sufficient length to extend into the container as shown more particularly in Fig. 1 and lies for a considerable part of its length in the slot 16 at the top of the dam 15. It then makes a substantially 90° bend downwardly and terminates at a point just short of touching the interior enclosed surface 31 of the dam 15.

The lower electrode 20 extends only a short

distance into the container and terminates on a downwardly bent portion about half-way between the glass pinch-seal and the straight vertical side of the dam 15, as shown in Figs. 1, 4 and 6.

An amount of mercury, or similar electrical conducting fluid, sufficient to bridge the dam when the entire device is slightly tilted, as shown in Fig. 6, is placed in the container.

There should, however, be insufficient mercury to bridge the dam when the container is in a substantially horizontal position, or slightly inclined in a direction opposite to that shown in Fig. 6.

The insertion of the Dumet wire with the electrodes welded thereto can be accomplished by machinery, and the method for so doing is more particularly described in a copending application, Serial No. 228,043, filed October 22, 1927.

However, in order to prevent the possibility of the electrode from cracking the glass in the seal, we prefer to employ substantially pure nickel for making the electrodes. We have found that a slight space remains between the nickel and the glass, forming a sort of air pocket or gas pocket. This we account for on the theory that the nickel, being heated substantially to red heat during the operation of sealing the Dumet wire and electrodes into the glass, becomes oxidized with the formation of a film of nickel oxide. As the tube after complete assembly is exhausted of all air through a tubulation forming a part of the glass container (of which tubulation only the remaining "tip" 21 is shown in the drawings), and filled with hydrogen and heated to remove all traces of oxygen, and again exhausted and refilled with hydrogen, it is highly probable that the film of nickel oxide is reduced to metal, thus slightly diminishing the diameter of the electrodes and thus leaving the minute space between it and the glass. Another possible explanation is that nickel always has absorbed or dissolved in it a small amount of the gases of the atmosphere, and these escape from the surface of the nickel electrode during the sealing operation, thus pushing the glass away from the nickel.

Irrespective of the correct theoretical explanation of the phenomenon just described, the fact remains that even though the nickel electrodes may become heated by the passage of electric current through them, the resultant expansion is compensated for by the minute space between them and the glass seal, and the cracking of the glass at this point is prevented. With materials other than nickel, difficulty caused by end expansion has been encountered. We have, however, by our use of nickel electrodes, overcome this difficulty, and consider this feature as one of the objects attained by our invention.

Another decided advantage inherent in

the use of nickel electrodes is the fact that the nickel will not contaminate the mercury. Furthermore, a better electrical contact is formed between nickel and mercury by reason of the slight coating or wetting of the nickel by the mercury. This causes a change in the nature of the meniscus at the point where the nickel electrode dips into the mercury.

The phenomena of wettability has a pronounced effect upon the meniscuses of liquids in contact with solid objects dipping into them. For example, an iron rod dipping into water produces a meniscus which is concave and extends above the surface of the water, reaching up along the iron rod, as illustrated in Fig. 8. A similar iron or tungsten rod dipping into mercury, which does not wet the rod, causes a meniscus of the opposite type, the mercury in this case dipping downwardly below its surface, as seen in Fig. 9. A nickel rod, however, is partially wetted by mercury and practically merely punctures the surface with a hardly appreciable meniscus, as shown in Fig. 10.

The resultant electrical contact is more perfect and has less resistance than one between mercury and some metal which is not at all wetted by the same. Instead of making the upper electrode 19 with a rectangular bend, as shown in Fig. 1, we may adopt the construction of the modification illustrated in Fig. 5. In that case the electrode 19a bends downwardly almost immediately after entering the container 11 and terminates at relatively the same point within the annular dam 15 as does the rectangularly bent electrode 19 in Fig. 1. This makes it possible to use a short electrode, and the internal resistance of an electrical contactor made according to the modification shown in Fig. 5 will be lower than that of one made according to the modification shown in Figs. 1, 2 and 6. Both constructions, however, are to be considered within the scope of our present invention. Again, it may be desirable to modify either one of the previous structures in order that the electrodes 19 or 19a terminate outside of the annular dam as shown more particularly in Fig. 7.

One of the particular advantages of our improved construction lies in the ability to employ a mechanically made pinch-seal through which both of the conductors welded to the electrodes enter the container 11. The upper split or slot 16, in the substantially annular dam 15, permits one electrode to contact with the portion 18 of the mercury lying in that section of the container furthest away from the pinch seal.

It is to be understood that the container 11 besides housing the mercury and electrodes contains an atmosphere of a gas inert to mercury and nickel as, for example, hydrogen. This gas may be either at substantially atmos-

pheric pressure, or above or below that pressure. The use of a pinch seal such as that shown also makes it possible to employ a shorter tube and less mercury.

5 Of course, it is apparent that the split sleeve or dam 22, as shown in Figs. 3 and 4, is not essential to the employment of a pinch seal construction because the construction shown in Fig. 5 may be employed which does 10 not necessitate the use of a dam having a split portion.

Obviously modifications in the construction embodying our improved form of electrical contactor are to be construed as within the 15 scope of our invention, for which we claim:

1. A tiltable electrical contactor comprising an hermetically sealed elongated container, electrodes of a material not adversely affected by mercury entering said container at the same end thereof and spaced from one another within said container and longitudinally thereof, a split annular dam of a refractory material nonwettable by mercury disposed within the container wholly 25 beyond where said electrodes enter the same, and a body of metallic conducting fluid adapted to establish electrical connection between the electrodes, said body of fluid being in sufficient amount to cover said dam when 30 the contactor is tilted to the conducting position but in insufficient amount to cover said dam when the contactor is tilted into interrupted position, one of said electrodes terminating within said dam.

35 2. A tiltable electrical contactor comprising an hermetically sealed container, electrodes of a material not adversely affected by mercury, a split annular dam of a refractory material nonwettable by mercury disposed within the container wholly beyond where said electrodes enter the container and a body of metallic conducting fluid adapted to establish electrical connection between the electrodes, said body of fluid being in sufficient 40 amount to cover said dam when the contactor is tilted to the conducting position but in insufficient amount to cover said dam when the contactor is tilted into interrupted position, one of said electrodes lying 45 for a portion of its length within the split portion of the said dam.

50 3. A tiltable electrical contactor comprising an hermetically sealed container, electrodes of a material not adversely affected by mercury, a split dam of a refractory material of substantially tubular form and nonwettable by mercury located wholly beyond where said electrodes enter the container and a body of metallic conducting fluid adapted 55 to establish electrical connection between the electrodes, said body of fluid being in sufficient amount to cover said dam when the contactor is tilted to the conducting position but in insufficient amount to cover said dam when 60 the contactor is tilted into interrupted position.

65 tion, one of said electrodes lying at least partially within the split portion of the dam and terminating within said dam.

4. A tiltable electrical contactor comprising an hermetically sealed container, electrodes of a material not adversely affected by mercury entering said container at the same end thereof, a split annular dam of a refractory material nonwettable by mercury of substantially tubular form, said tube having tapering sides and being located wholly beyond where said electrodes enter said container the electrodes, and a body of metallic conducting fluid adapted to establish electrical connection between the electrodes, said body of fluid being in sufficient amount to cover said dam when the contactor is tilted to the conducting position but in insufficient amount to cover said dam when the contactor is tilted into intermediate position, one 85 of said electrodes terminating within said dam.

5. A tiltable electrical contactor comprising an hermetically sealed tube, metallic electrodes passing through a pinch-seal at one end of said tube and sealed therein, a split annular dam of refractory material positioned on the interior of said tube and disposed wholly beyond where said electrodes enter the tube, at least one of said electrodes 90 passing at least partially within the split portion of said dam and a body of mobile electrically conducting fluid adapted to establish electrical connection between said electrodes, and an atmosphere of inert gas in said 100 tube.

6. In an electrical contactor of the type described, the combination of a substantially annular split refractory dam secured to the interior of the container and with an elongated electrode passing at least partly through the split portion of said dam.

7. A tiltable electrical contactor comprising an hermetically sealed container, electrodes contained therein, a mobile body of electrically conducting fluid in contact with one of said electrodes but adapted to be divided into two bodies of mobile conducting fluid, one of which remains in contact with one electrode, a split annular dam disposed wholly beyond one of said electrodes and dividing said bodies of mobile conducting fluid into two portions and an atmosphere of inert gas within said container, at least one of said electrodes passing at least partly through the 110 split portion of said dam.

8. In an electrical contactor of the type described, the combination of a metallic electrode in said contactor in permanent contact with a body of mercury, a split annular refractory heat-insulating dam adapted to hold said body of mercury in contact with said electrode, a second electrode in said contactor and passing for a portion of its length through the split in said dam,

a second body of mercury adapted to contact with said second electrode, the quantity of said second amount of mercury being such that on tilting the contactor said second body 5 of mercury passes over said dam, and merging with the first body of mercury, establishes electrical connection between the first and second electrodes.

9. In an electrical contactor of the type 10 described, the combination of a metallic electrode inwardly disposed in said contactor and in permanent contact with a body of mercury, a split annular heat-insulating dam of refractory material adapted to hold said body 15 of mercury in contact with said electrode, a second electrode passing out of the container from the same end as the first electrode and passing for a portion of its length through the dam; a second body of mercury 20 adapted to contact with said second electrode, the quantity of said second amount of mercury being such that on tilting the contactor said second body of mercury passes over said dam and, merging with the first body of 25 mercury, establishes electrical connection between the first and second electrodes.

10. In an electrical contactor of the type 30 described, the combination of a nickel electrode inwardly disposed in said contactor and in permanent contact with a body of mercury, a heat-insulating split annular dam of refractory material adapted to hold said body 35 of mercury in contact with said electrode, a second electrode entering said contactor at the same end as the first electrode and passing for a portion of its length through the slot in said dam, a second body of mercury 40 adapted to contact with said second electrode, the quantity of said second amount of mercury being such that on tilting the contactor said second body of mercury passes over said dam and, merging with the first body of mercury, establishes electrical connection between the first and second electrodes.

11. A tiltable electrical contactor comprising 45 an hermetically sealed container, two electrodes entering said container through a pinch seal at one end thereof, a dam consisting of a split tube of refractory material not adversely affected by mercury in said container and disposed beyond one of said electrodes, the second electrode passing through the slot in said dam, a body of mercury 50 adapted to establish a path for electric current between said electrodes and of sufficient quantity to cover said dam when the contactor is tipped into conducting position, and an atmosphere of hydrogen within said container.

12. A tiltable electrical contactor comprising 55 an hermetically sealed glass container, Dumet leading-in wires sealed in the wall thereof, nickel electrodes within said container that are attached to said Dumet wires

immediately adjacent to the wall of the container, a dam consisting of a split tube of refractory material nonwettable by mercury disposed in said container wholly beyond one of said electrodes, the second electrode 70 passing through the slot in said dam substantially to the further side of the same, a body of mercury adapted to connect electrically said electrodes and of sufficient quantity to cover said dam when the contactor is tipped into conducting position, and an atmosphere of a gas inert to mercury within said container.

13. In an electrical contactor comprising 75 an hermetically sealed vessel containing a metallic conducting fluid and two electrodes entering said vessel through a pinch-seal at one end thereof, means for dividing the conducting fluid into two unequal portions comprising a tubular dam of refractory material, said dam being split to permit one electrode to traverse said dam and contact with the conducting fluid at the far side of said dam.

14. An electrical contactor comprising a 80 hermetically sealed elongated container, a plurality of electrodes sealed in one end thereof through the medium of a pinch seal and spaced from one another in said seal transversely of the container and in said container longitudinally thereof, a refractory dam disposed interiorly of said container, one only of said electrodes terminating within the area of said dam and the other of said electrodes terminating at the adjacent end of 85 said container and spaced from the container wall and from the adjacent end of said dam, and a body of mercury housed in said container for making and breaking the electric circuit between said electrodes.

15. An electrical contactor comprising a 90 hermetically sealed elongated container, a plurality of electrodes sealed in one end thereof through the medium of a pinch seal, a refractory dam disposed interiorly of said container, one only of said electrodes terminating within the area of said dam and the other of said electrodes terminating at the adjacent end of 95 said container and spaced from the container wall and from the adjacent end of said dam, and a body of mercury housed in said container for making and breaking the electric circuit between said electrodes.

16. An electrical contactor comprising a 100 hermetically sealed elongated container, a plurality of electrodes sealed through one end thereof by means of a pinch seal and spaced from one another in said seal transversely of the container and in said container longitudinally thereof, a refractory dam disposed interiorly of said container and spaced 105

from the pinch seal to provide a recess to receive a body of mercury, said dam having an inclined surface that slopes downwardly away from said pinch seal, one of said electrodes terminating within said recess intermediate said dam and said pinch seal and the other electrode terminating within the area of said dam, and a body of mercury filling said recess and the excess of said mercury being movable on the tilting of the contactor for making and breaking the electric circuit between said electrodes.

17. An electrical contactor comprising a hermetically sealed container, a plurality of electrodes sealed in one end thereof, a refractory dam disposed interiorly of said container and spaced from the sealed end of said container to provide a recess to receive a body of mercury, said electrodes being spaced transversely of said container at the seal and longitudinally of said container at their exposed contacting surfaces and one of said electrodes terminating within said recess intermediate said dam and said seal and the other electrode terminating within the area of said dam, and a body of mercury filling said recess and the excess of said mercury being movable on the tilting of said contactor for making and breaking the electric circuit between said electrodes.

18. An electrical contactor comprising a hermetically sealed container, a plurality of electrodes sealed in one end thereof through the medium of a pinch seal, a refractory dam disposed interiorly of said container and spaced from the sealed end of said container to provide a recess to receive a body of mercury, said electrodes being spaced transversely of said container at the pinch seal and the lower electrode terminating within said recess intermediate said dam and said pinch seal and the upper electrode extending longitudinally of said container and terminating within the area of said dam, said dam having an inclined surface sloping downwardly in the direction of the electrode that terminates within the area of the dam, and a body of mercury filling said recess and the excess of said mercury being movable on the tilting of said contactor for making and breaking the electric circuit between said electrodes.

In witness whereof we have hereunto subscribed our names.
